CERTIFIED MILK CASE

Edward M. Pennock and Lloyd Hale, Minneapolis,
Minn., assignors to G. H. Tennant Company,
Minneapolis, Minn., a corporation of Minnesota

Application March 4, 1931, Serial No. 519,917

1 Claim. (Cl. 217—20)

Certified and other special grades of milk that sell at a premium are ordinarily bottled in the country and shipped or trucked to town in some type of box or container that can be iced. As such 5 milk is often used for babies and invalids, it is necessary to keep it properly refrigerated until the time it is used. Heretofore, boxes commonly used for this purpose have not been easy to keep sanitary; some of them do not have metal linings 10 and those that do have a metal lining are constructed so that the lining is fastened permanently to the inner walls of the case. The bottles heretofore were ordinarily kept from bumping together by the use of permanently fixed or loose 15 wooden partitions.

Our certified milk case is designed to overcome these objectionable features and to provide a water-tight loose and removable inner metal liner or filler which can be taken out and cleaned and 20 which can be easily replaced if it gives out before the outer case is worn out.

A further feature of the invention resides in the metal rack which can be kept clean and sanitary and is more durable than wooden spacers as used 25 in the old type of certified milk boxes. The removable filler may be provided with a slideable and foldable handle which can be folded down out of the way against the dividing wires of the filler or can be drawn up into operative position so that 30 the filler can be used as a carrier when it is desired. The filler is constructed with peculiar type rivet-like stay rods which extend from side to side of the filler and which are formed with shoulders on the ends adapted to close the opening in 35 the side wall through which the rivet rods extend to form a water-tight joint. This provides an economical structure of manufacture in that these rods form the spacers or partitions for dividing the filler into compartments for the bottles. 40

The removable rack or filler of my case provides a milk case which is particularly adapted for use for certified milk and gives a construction where the case can be converted from a twelve quart to a twenty pint, or a thirty or sixty half-pint, merely by changing the racks in the case. This interchangeable feature of the racks or fillers in the case is important, as the same 45 size outer case may be converted into these different sizes readily by changing the filler within the same. The metal rack may be of a riveted structure with or without a bottom portion, or it may be made by welding the parts together to 50 provide the water tight filler portion with the

partitions in the same to divide the filler for receiving the different size bottles as defined.

It is also a feature to provide a holder or filler for the bottles in the certified milk case or carrier in which only two bottles may be contained 5 and where the stay bolts divide the filler into separate compartments for each bottle. This smaller filler constitutes the same structure in the removable filler or liner for the certified milk case.

The invention includes a rivet stay rod of a peculiar nature, wherein shoulders are provided on the ends of the rod adjacent a frustro-conical formed end which projects beyond the shoulders. This rivet stay rod provides the spacer 10 between the sides of the fillers and acts to form an effective means of providing a water-tight joint between the rod and the metal side wall when the stay rivet rod is anchored in place by upsetting the outer end of the frustro-conical 15 portion. In other words, when the ends of the stay rod rivet are riveted to the side walls, a tight joint is provided. This is an important structure because it prevents moisture from getting in around the riveted end of the rod and rusting out 20 the side wall so that the rods in a short time would become loose. In crate structure for milk bottles and the like, it is believed this is a new development.

These features, together with other details 30 and objects of the invention will be more fully and clearly set forth in the specification and claim.

In the drawings forming part of this specification:

Figure 1 is a perspective view of a certified 35 milk case, showing our removable filler box therein.

Figure 2 is a detail of a portion of a filler, showing the adaptation of a slideable folding handle 40 to the bars or stay bolts of the filler.

Figure 3 is a perspective view of the removable 45 filler or divider for the certified milk case, wherein an open bottom is provided, some of the stay bolts forming bottom means for the bottles.

Figure 4 is a perspective view, looking up from the bottom of the removable filler for certified cases with a closed bottom.

Figure 5 illustrates a small certified milk case 50 for two bottles of milk.

Figure 6 illustrates the removable filler for the certified milk case illustrated in Figure 5.

Figure 7 illustrates a sectional detail of the riveting or stay bolts or rods used in our removable fillers.

Figure 8 is a perspective view, a part of which is in section and part broken away, of one of the stay rods used in making our removable filler for certified milk cases.

5 The drawings illustrate our certified milk case A the outer casing portion of which is made of wood for the advantage of insulating and protecting the contents of the case. The case A is provided with a cover H which may be formed 10 with an inwardly projecting portion 10. This portion 10 may be covered with sheet metal if it is desired, to protect the same.

The certified milk case A is adapted to receive the removable filler B which is made with sheet 15 metal sides 11 and may be formed with a bottom portion 12 like the filler B, illustrated in Figure 4.

The filler illustrated in Figure 3 is formed without a bottom portion 12 and in this construction parallelly extending rivet stay rods C 20 are positioned close enough to each other and extended along the bottom of the filler B as illustrated in Figure 3 to form a bottom engagement or rest for milk bottles such as D. The filler B is provided with other stay rods C which are also 25 indicated as the stay rods 14 to distinguish them from the stay rods C which form the rests for the bottles held in the filler B. The stay rods C which act as rests or bottoms for the bottles we have termed 13 to distinguish them from the stay 30 rods 14. The stay rods 14 are extended between the sides 11 of the filler B in a manner so that some of the rods extend at right angles to other of the rods as illustrated in Figure 3. The rods 14 extending in one direction, that is, between 35 the parallel walls 11 of the filler B, extend in the same plane, then there is another set of these same rods extending at right angles to these first rods 14 that also extend in a horizontal plane, and these last rods are directly under the first 40 rods and contact at their points of intersection so that the rods 14 extending at right angles to each other between the sides 11 of the filler B form individual bottle compartments or spaces, such as E, to receive the bottles in the filler B 45 and hold them spaced apart from each other and to provide openings between the bottles so that ice may be packed in around the same.

It is desirable to have two or more sets of partitioning rods such as 14, each set extending at 50 right angles to each other like as illustrated in Figure 3, and one set being placed in a horizontal plane above the other set.

The spacer rivet rods C are of the construction illustrated in Figures 7 and 8, the body of 55 the rod 15 may be round or flat or any suitable formation, while each end is formed with a shoulder 16 and projecting from the shoulder a frusto-conical riveted portion 17 is provided which may be riveted over to form the rivet 60 head 18, like in Figure 7. The tapered end 17 provides a wedge shape which is tightened in the hole 19 when the head 18 is riveted over and the shoulder 16 helps to lock the end of the rod C with a water-tight joint connected to the 65 wall 11.

These rods C form the partitioning rods like 14 and also the bottom rods like 13, illustrated 70 in Figure 3. Where a bottom 12 of sheet metal is provided like in Figure 4, for the bottle filler B, there is no necessity of bottom rods 13. It is important, however, that the spacer rivet rods C have a structure of the nature described in their formation as set out in Figures 7 and 8, 75 because it is not desirable to have the water

from the ice leak out of the filler where a filler like B is used in the case A.

When a filler like B without a closed bottom as is illustrated in Figure 3 is used in the case A, then the case A itself is metal-lined and the 5 filler B is used therein.

It is also desirable to use a filler B in an ordinary case which is not metal-lined and where no ice is used so as to provide different forms of fillers B for the different cases like A. For 10 instance, it is very desirable to have the removable filler like B so that the case may be converted from a twelve quart to a twenty pint, or thirty or sixty half-pint, merely by changing the 15 fillers B. In other words, the spacer rods 14 are positioned differently in the different removable fillers B to give more or less compartments such as E for the bottles, and where smaller bottles are held in the case A, one filler B may be of a lower height and one placed on top of the other, 20 In this sense, the removable filler B is of extreme importance in providing a flexible case for milk bottles.

The corners 20 of the fillers B are angularly 25 disposed in relation to the walls 11 so as to provide a space in the crate case A which permits a reinforcing member 21 to be used in the inside of the case A at the corner, while the cut-off corner or angularly disposed portion 20 of the 30 fillers B extend across in front of these reinforcing corners 21 and leave a space for the corner member within the case. These fillers B are formed with a diagonal corner portion 20 which permits the filler B to slide into the case easily.

The fillers B may be provided with a sliding 35 foldable handle F which is formed with the loops 22 so that the handle can be folded down against the upper stay rivet 14 or lifted up as illustrated in dotted outline in Figure 2, to carry or lift the filler B. There are times when a handle of this 40 nature is practical for certified milk cases where it is desired to carry the contents of the filler B as a tray, particularly in lifting the bottles out of the collection plate.

It is also desirable to form the filler for the 45 case A as illustrated in Figure 6, in the form of a box-like tray member, having a deep construction adapted to receive the bottles D and where a couple of stay rivets C are used to divide the filler B into compartments to receive a couple of bottles. In this case the filler B is made of metal 50 with a closed bottom and is provided with two stay rivets which separate the tray B into two compartments. A smaller filler or tray illustrated in Figure 6 is adapted to fit into a tall case 55 such as A, illustrated in Figure 5, and this case may be provided with a hasp and eye G so that a lock can be placed upon the certified case A, if it is desired.

Heretofore, cases for certified milk have been 60 built with permanent spacers or dividers in the same of wood or other material, but they have not been formed with a removable and interchangeable filler such as E which may be made divided into more or less compartments for the desired 65 number of milk bottles to fit into the case A. The outer cases A may be made of a standard nature so that with the tray which is removable, such as B, the cases A may be converted into holders 70 for quart or pint bottles or half-pints, yet maintaining the same size case A and without any loss of time the trays or fillers B may be changed.

The important feature of removable fillers B resides in the structure with the stay rivets C which form joints between the rivets and the sides 75

or case of the tray or filler B and the interchangeable nature or removable feature of the filler itself. Owing to the fact that the trays or fillers B must be provided with divisions to receive the 5 bottles in the individual compartments E and for the reason that it is necessary to have these trays or fillers sanitary so that they can be thoroughly cleansed to permit for the proper care in handling certified milk, it is important that they are removable and that they be of a strong, durable 10 nature so that they will withstand the handling and also protect the bottles when they are in place in the case A. The form and construction of the filler B is also important in accomplishing 15 the desired results in conjunction with the case A. The fillers B may be used with suitable cases without the cover portion where it is desired to provide interchangeable inner trays or spacers to provide for the individual spaces for the bottles. 20

In accordance with the patent statutes, we have described and set forth the principles of our in-

vention, however, we desire to have it understood that the description and drawings are only suggestive and that the invention should be considered within the scope of the following claim.

We claim:

In combination with a rectangular outer casing formed of wood having a cover portion adapted to be closed over said casing, a removable bottle display tray positioned in said casing, diagonally disposed corner portions formed in said tray to provide spaces at the corners in said casing, and a series of rivet rods extending between the sides of said tray to provide spacers for dividing said tray into individual bottle compartments, said rods extending at right angles to each other and disposed in sets of horizontal planes, said rods virtually touching each other at their point of intersection, and rivet ends formed on said rods to unite the ends of said rods with a water-tight joint with said side wall. 15 20
